Design for Bazzin's Board

Wes. 1734

James A. Bazine, of Banton, Massachusetts.

Letters Patent No. 1734, dated March 17, 1869.

The schedule referred to in these Letters Patent and making part of the same.

To all whom it may concern:

Be it known that I, James A. Bazine, of Banton, in the County of Norfolk and State of Massachusetts, have invented a new and original design for a "Solitaire Board;" and I do hereby declare that the following is a full and exact description of the same. My improvement consists in the union of two solitaire boards A, and B, of the common construction, the boards being connected by the neck or vacant central space C. The holes to receive the pins or balls are shown at a, b, c, &c. on the part A, and a', b', c', &c. on the part B.

I do not claim any new form or design in the arrangement of the holes used in playing the game, but I claim the design or configuration produced by the union of the two sets of holes upon the same board, as shown in the drawings at A, and B.

Witnesses,

Sam'l Batchelder Jr.
R. C. Apthorp.

James A. Bazine. (Seal.)
